CATIONIC MONOAZO DYESTUFFS CONTAINING A DICARBOXIMIDO RADICAL

John G. Fisher and James M. Straley, Kingsport, Tenn.,
assignors to Eastman Kodak Company, Rochester,
N.Y., a corporation of New Jersey
No Drawing. Filed Oct. 8, 1965, Ser. No. 494,253
7 Claims. (Cl. 260—158)

ABSTRACT OF THE DISCLOSURE

Quaternary thiazolyl- and benzothiazolyl-azo-indole compounds having a dicarboximidoalkyl group attached to the indole nitrogen atom which are useful as dyes for acrylic and modacrylic textile materials.

This invention relates to novel compounds containing a dicarboximido radical, and more particularly to cationic azo compounds, such as cationic azo dyestuffs, containing a dicarboximido radical.

The azo compounds of the invention have the general formula

wherein R=a 2-thiazolyl radical, i.e.,

or a 2-benzothiazolyl radical, i.e.,

wherein

x=hydrogen; lower alkyl; e.g. methyl, ethyl, propyl, butyl; aryl, e.g. phenyl; halogen, e.g. chlorine; acyl, e.g. acetyl; haloalkyl, e.g. trifluoromethyl;

y=hydrogen; lower alkyl, e.g. methyl, ethyl, propyl, butyl; acyl, e.g. acetyl; lower alkylsulfonyl, e.g. methylsulfonyl; acylamido, e.g. acetamido and the like;

R3=lower alkyl, e.g. methyl; aryl, e.g. phenyl, benzyl;

R4=hydrogen; lower alkyl, e.g. methyl, propyl, alkoxy, e.g. methoxy; e.g. acyl, e.g. acetyl; acylamido, e.g. acetamido; halogen, e.g. chlorine; thiocyanato; alkylthio, e.g. methylthio; carboalkoxy, e.g. carbomethoxy; sulfamoyl; N-alkylsulfamoyl, e.g. N-methylsulfamoyl; N-N-dialkylsulfamoyl, e.g. N,N-diethylsulfamoyl; alkylsulfonyl, e.g. methylsulfonyl, cyano and the like;

R1=an indolyl radical, i.e.,

wherein

R5=lower alkyl, e.g. methyl; aryl, e.g. phenyl;

R6=hydrogen; lower alkyl, e.g. methyl; alkoxy, e.g. methoxy; carboalkoxy, e.g. carbomethoxy; halogen, e.g. chlorine; nitro; cyano and the like;

R2=lower alkylene, e.g. $-\text{CH}_2-\text{CH}_2-$,
 $-\text{CH}_2-\text{CH}_2-\text{CH}_2-$

2

Z=a dicarboximido radical, i.e.,

wherein

B=carbon atoms necessary to complete the ring, such as vinylene, e.g. $-\text{CH}=\text{CH}-$; alkylene, e.g.
 $-\text{CH}_2-\text{CH}_2-$

o-phenylene, e.g.

and the like; and A=an anionic material, e.g.

and the like, i.e. an acid anion.

Representative dicarboximido radicals Z are: succinimido, phthalimido, tetrachloro phthalimido, tetrahydro phthalimido, hexahydro phthalimido, 4-carboxy phthalimido, 3-nitro phthalimido, 3-methyl phthalimido, 3-aminophthalimido, glutarimido, bicyclo[2.2.1]-5-heptene-2,3-dicarboximido

1,8-naphthalimido, citraconimido, cycloalkanedicarboximido e.g.

alkyl succinimido e.g.

alkenyl succinimido e.g.

camphorimido

The azo compounds of the invention are prepared by coupling the diazonium salts of well known 2-aminothiazoles or 2-aminobenzothiazoles having the formulae

with dicarboximido alkyl indole coupling components which have the formula

wherein x , y , Z , R_2 , R_3 , R_4 , R_5 and R_6 are the same as defined above. The azo dye thus formed is treated, usually at an elevated temperature, with an alkylating agent such as dimethyl sulfate, methyl-p-toluene sulfonate, methyl iodide, benzyl bromide or the like, either in the presence or absence of a solvent, to yield the cationic dyestuff.

The carboximido alkyl indoles are prepared by reacting an aminoalkylindole with an anhydride, such as succinic anhydride, at an elevated temperature. The aminoalkylindole coupling components are prepared by catalytic reduction of a cyanoalkylindole. The latter compounds may be prepared by reaction of a chloroalkylindole with the alkali metal salt of the indole or, in the case of β -cyanoethylindole, by reacting acrylonitrile with the indole.

The following examples will serve to illustrate the preparation of the couplers of the invention and the formation of the dyes from them.

EXAMPLES OF CARBOXIMIDO ALKYL INDOLE COUPLERS

Preparation of 1- β -cyanoethyl-2-phenylindole

An amount of 50 ml. of acrylonitrile was added to a solution of 108 g. of 2-phenylindole, 9 ml. of Triton B and 1 g. of hydroquinone in 300 ml. of 1,4-dioxane. The reaction mixture was heated for 8 hr. at 95° C., allowed to cool, acidified with phosphoric acid and drowned in water. The oil which separated solidified on standing. The yield of 1- β -cyanoethyl-2-phenylindole was 136.5 g. and the product has the structure:

Preparation of 1- γ -aminopropyl-2-phenylindole

An amount of 100 g. of the above product was reduced in an autoclave under hydrogen pressure in 400 ml. of alcohol and 50 g. of anhydrous ammonia. The product was distilled under vacuum yielding 68 g. of 1- γ -aminopropyl-2-phenylindole boiling at 185-6° C. at 0.8 mm. and has the structure:

Preparation of 1- γ -succinimidopropyl-2-phenylindole

An amount of 30 g. of 1- β -cyanoethyl-2-phenylindole and 12 g. of succinic anhydride were gradually heated to 160° C. and held at 160-180° for 1.5 hr. The melt was poured into 200 ml. of alcohol and the crystalline product filtered off and dried. The yield was 32.6 g. and the product has the structure:

EXAMPLES OF THE DYES

Example 1

An amount of 10 ml. of 1-5 acid (1 part propionic: 5 parts acetic) was added to a solution of nitrosyl sulfuric acid prepared from .72 g. of NaNO₂ and 5 ml. of H₂SO₄. 1.0 g. of 2-aminothiazole was added keeping the temperature below 5° C., then a second portion of 10 ml. of 1-5 acid was added below 5° C. The diazotization was completed by stirring at 3 to 5° C. for 2 hr. The diazo solution was added to a solution of 3.32 g. of 1- γ -succinimidopropyl-2-phenylindole in 20 ml. of 1-5 acid cooled in an ice bath. The coupling mixture was buffered by addition of solid NH₄OAc keeping the temperature below 10° C. After 2 hr. standing with intermittent stirring the dye was precipitated by addition of 800 ml. of water. It was collected on a filter, washed well with water and dried at room temperature. The dye has the structure:

Example 2

An amount of 1 g. of the dye of Example 1 was heated in 10 ml. of dimethyl sulfate at 95-100° C. for 1 hr. After drowning with ether the precipitated quaternary dye was dissolved in water, filtered and reprecipitated by addition of NaI. It dyes acrylic fibers in fast red shades. This dye has the formula:

Example 3

An amount of 1 g. of a dye prepared as in Example 1 substituting 1- γ -phthalimidopropyl-2-phenylindole for the coupler, was dissolved in 40 ml. of dry chlorobenzene by heating. 1 ml. of dimethyl sulfate was added to the hot solution and after stirring 1 hr. at 95-100° C. the reaction mixture was allowed to cool to room temperature. The precipitated cationic dyestuff was filtered off, washed with hexane and dried in a vacuum desiccator. This dye imparts red shades to acrylic fibers which show very good fastness properties. It has the structure:

Example 4

An amount of 5 g. of a dye prepared as in Example

1 substituting 2-amino-4-phenylthiazole for the diazo component, was dissolved in 35 ml. of acetonitrile containing 1 ml. of methyl iodide. The solution was heated at reflux for 3.5 hr., allowed to cool and the quaternized dye filtered off. It dyes acrylic fibers in reddish violet shades and has the structure:

In accordance with the method of Examples 1-4, a variety of dyes were prepared as illustrated in the following table. The color is that obtained on acrylic fibers.

TABLE

Examples	X	Y	R ₃	A(-)	R ₅	R ₂	R ₆	B	Color
5.....	CH ₃	H		Br		-C ₂ H ₄ -	H	-C ₂ H ₄ -	Bluish-red.
6.....	CF ₃	H	CH ₃	I		-C ₃ H ₆ -	H	-C ₂ H ₄ -	Reddish-orange.
7.....	H	H	CH ₃	I		-C ₃ H ₆ -	-CO ₂ C ₂ H ₅	-C ₂ H ₄ -	Red.
8.....	H	H	CH ₃	I		-C ₃ H ₆ -	Cl	-C ₂ H ₄ -	Red.
9.....	CH ₃	CH ₃	CH ₃	Cl		-C ₃ H ₆ -	H	-C ₂ H ₄ -	Bluish-red.
10.....	H	C ₆ H ₅ SO ₃	CH ₃	I		-C ₃ H ₆ -	H	-C ₂ H ₄ -	Orange.

Example 11

An amount of 1.5 g. of 2-aminobenzothiazole was dissolved in 24 ml. of water and 14 ml. of H₂SO₄. A solution of nitrosyl sulfuric acid prepared from .72 g. of NaNO₂ and 5 ml. of H₂SO₄ was added at 4 to 6° C. After stirring for 2 hr. at this temperature the diazo solution was added to a cooled solution of 1- γ -succinimidopropyl-2-phenylindole in 20 ml. of 1-5 acid. The coupling mixture was buffered with NH₄OAc and allowed to stand for 2 hr. with intermittent stirring. The dye was isolated by drowning in 1 l. of water, collecting on a filter, washing with water and drying. The dye has the structure:

45

50

Example 12

An amount of 1 g. of the dye of Example 11 was dissolved in 40 ml. of dry chlorobenzene. After addition of .75 g. of methyl-p-toluenesulfonate in 10 ml. of dry chlorobenzene the reaction mixture was stirred and heated on the steam bath for 1.5 hr. After cooling, the quaternized dye was filtered, washed with hexane and dried in a vacuum desiccator. It dyes acrylic fibers in slightly bluish-red shades which show good fastness properties. This dye has the structure:

65

70

75

Example 13

1 g. of a dye prepared as in Example 11 substituting 1- γ -succinimidopropyl-2-methylindole as the coupler was quaternized by heating in 10 ml. of dimethyl sulfate at 95-100° C. for 1 hr. The red solution was drowned in ether and the sticky solid thus precipitated was dissolved in water, the solution filtered and the dye precipitated as

the iodide by addition of NaI. It dyes acrylic fibers in red shades. The formula is:

Example 14

One gram of the azo dye prepared by coupling 2-diazo-6-methoxybenzothiazole to 1- γ -succinimidopropyl-2-phenylindole was heated in 5 ml. of methyl-p-toluenesulfonate at 95-100° C. for 3 hr. The pink solution was drowned in ether and the solid collected on a funnel. For purification this dye was dissolved in 350 ml. of hot water, treated with .2 g. of charcoal, filtered and the solution allowed to cool. Potassium iodide was added and the dye collected on a funnel, washed with a little water and dried. This dye imparts reddish-violet shades to acrylic fibers and has the structure:

In accordance with the method of Examples 6-14, a variety of dyes were prepared as illustrated in the following Table. The color is that obtained on acrylic fibers.

A particularly efficacious group of modacrylic polymers is an acetone soluble mixture of (A) 70-95% by weight of a copolymer of 30-65% by weight of vinylidene

Textile materials dyed by the azo compounds are characterized by containing at least about 35% combined acrylonitrile units and up to about 95% acrylonitrile units, and modified, for example, by 85-5% of vinyl pyridine units as described in U.S. Patents 2,990,393 (Re. 25,533) and 3,014,008 (Re. 25,539) or modified by 65-5% of vinyl-pyrrolidone units, for example, as described by U.S. Patent 2,970,783, or modified with 65-5% acrylic ester or acrylamide units as described in U.S. Patents 2,879,253, 2,879,254 and 2,838,470. Similar amounts of the other polymeric modifiers mentioned above are also useful. A preferred group of the copolymers readily dyeable with the azo dyes are the modacrylic polymers such as described in U.S. Patent 2,831,826 composed of a mixture of (A) 70-95% by weight of a copolymer of from 30 to 65% by weight of vinylidene chloride or vinyl chloride and 70-35% by weight of acrylonitrile, and (B) 30-5% by weight of a second polymer from the group consisting of (1) homopolymers of acrylamidic monomers of the formula

wherein R₇ is selected from the group consisting of hydrogen and methyl, and R₈ and R₉ are selected from the group consisting of hydrogen and alkyl groups of 1-6 carbon atoms, (2) copolymers consisting of at least two of said acrylamidic monomers, and (3) copolymers consisting of at least 50% by weight of at least one of said acrylamidic monomers and not more than 50% by weight of a polymerizable monovinyl pyridine monomer.

chloride and 70-35% by weight of acrylonitrile and (B) 45 30-5% by weight of an acrylamide homopolymer having the above formula wherein R₁, R₂ and R₃ are as described above. Specific polymers of that group contain 70-95% by weight of (A) a copolymer of from 30-65% by weight 50 of vinylidene chloride and 70-35% by weight of acrylonitrile and (B) 30-5% by weight of a lower N-alkyl-acrylamide polymer such as poly-N-methacrylamide, poly-N-isopropylacrylamide and poly-N-tertiarybutylacrylamide.

55 The following example illustrates one way in which
the azo compounds of the invention can be used to dye
acrylonitrile polymer textile material. 1 gram of dye is
dissolved by warming in 5 cc. of methyl Cellosolve. A
2% aqueous solution of a non-ionic surfactant, such as
Igepal CA (a polymerized ethylene oxide-alkylphenol con-
60 densation product), is added slowly until a fine emulsion
is obtained and then the dye mixture is brought to a vol-
ume of 200 cc. with warm water. 5 cc. of a 5% aqueous
solution of formic acid or acetic acid are added and then
65 10 grams of fabric made from an acrylic fiber is entered
and in the case of Orlon 42 the dyeing is carried out at
the boil for one hour. In the case of materials made of
Verel acrylic fiber the dyebath temperature should not
exceed 90° C. in order to avoid damage to the fiber. The
dyed material is then washed well with water and dried.

70 The invention has been described in considerable detail with particular reference to certain preferred embodiments thereof, but it will be understood that variations and modifications can be effected within the spirit and scope of the invention as described hereinabove, and as
75 defined in the appended claims.
